UNITED STATES PATENT OFFICE

2,172,600

TOOTH-BRUSH APPLIANCE

Fred Van der Werth, Oak Park, Ill.

Application December 17, 1937, Serial No. 180,429

3 Claims. (Cl. 15—247)

The invention relates to tooth brush appliances and more particularly to an inexpensive disposable tooth cleaner which may be easily and quickly attached to a tooth brush. Although a tooth brush is the best known instrument to effectively remove particles of foreign matter from the crevices between the teeth it is inefficient for removing tartar deposits from or for polishing the teeth. This is because the bristles are ineffective as a buffer or polisher.

It is, therefore, an object of the invention to provide a polishing or buffering appliance for a tooth brush, which is inexpensive and which may be disposed of after a single use.

Another object is to provide a tooth polishing appliance which may be readily and securely attached to and quickly removed from a tooth brush.

The foregoing and such other objects of the invention as will more fully appear hereinafter as the description proceeds will be more readily understood from a perusal of the following specification, reference being had to the accompanying drawing, in which:

Fig. 1 is a perspective view showing one embodiment of the tooth polishing appliance attached to a tooth brush.

Fig. 2 is a perspective view of the appliance illustrated in Fig. 1.

Fig. 3 is a fragmentary side elevational view of the tooth brush, showing the appliance, in section, attached thereto.

Fig. 4 is a transverse sectional view taken on line 4—4 of Fig. 2.

Fig. 5 is a perspective view showing a modified construction.

Fig. 6 is a transverse sectional view through a tooth brush showing the appliance illustrated in Fig. 5 attached thereto.

Fig. 7 is a perspective view of another modified construction.

Fig. 8 is a perspective view showing another modified form.

Referring particularly to Figs. 1 to 4, inclusive, of the drawing, the appliance preferably consists of a thin pliable fabric strip suitably cut and folded intermediate its ends to provide a substantially rectangular jacket 11 having inwardly disposed corner seams 12. The two end portions of the strip have their side margins folded inwardly toward each other to provide reinforced extensions or tabs 14 and 14a. As shown, the tab 14a is considerably longer than tab 14 for a purpose to be more fully explained hereinafter. A transverse opening 15 is provided in each tab ad-

jacent the respective end wall 13 of jacket 11 and the short tab 14 also has a transverse opening 16 adjacent its free end.

To assemble for use, the brush handle 17 is inserted through the transverse opening 15 in the long tab 14a and the jacket 11 is slipped over the bristles 18. The short tab 14 then is turned back along the bottom of the brush with the projecting end portion 19 of the handle extending through the transverse opening 15 in said tab, as best shown in Figs. 1 and 3. The free tapered end 21 of the tab 14a then is inserted through the opening 16 in tab 14 and the tab 14a is drawn towards the end of the handle and is adapted to be held thereagainst by the user to tightly retain the jacket 11 in place. It is obvious that the appliance may readily be mounted and securely held in place on the tooth brush, the bristles of which serve as a resilient foundation for the fabric jacket, and that after use it may be easily and quickly removed and disposed of.

To prevent tearing of the tabs 14—14a, particularly at the openings 15 and 16, it is desirable that a plurality of rows of reinforcing stitches 22 extend longitudinally in each tab.

In the appliance illustrated in Figs. 5 and 6, the jacket 11a preferably is formed by folding a fabric strip longitudinally to bring its complementary edges together and then to sew said edges around one end as at 23 and along one longitudinal edge, as at 24, for a short distance from said sewed end. The unsewed portion of the strip is slit along the fold, as at 25, to provide two separate holding or securing tabs 26, which, if desired, may be wrapped about the brush 35 handle.

The appliance illustrated in Fig. 7 differs from that just previously described in that the strip of material is folded over upon itself inwardly from one end and has its complementary edges 27 turned inwardly and sewed to provide a jacket 11b and a gripping portion 28.

In Fig. 8 the jacket 11c is formed substantially like that shown in Fig. 7 but differs from that structure in that the jacket extends the entire length of the appliance so that the entire or at least a greater portion of the tooth brush is enveloped.

Although exemplary embodiments of the invention have been shown in detail in the accompanying drawing and specifically described in the foregoing description it is to be understood that the disclosures are illustrative rather than restrictive and that the invention is not intended

to be limited thereby except as required by the state of the prior art.

I claim:

1. In combination with a tooth brush, a bur-
5 nishing appliance including a fabric jacket of
a size to fit snugly over the bristles of said brush,
a short tab on one end of said jacket, a long
tab on the other end of said jacket, said tabs
each having an opening adjacent the jacket, one
10 of said openings receiving one end portion of the
brush therethrough and the other receiving the
handle of said brush therethrough, and the short
tab having a second opening adjacent its free end
through which the long tab may be threaded,
15 said long tab being adapted to extend along the
handle of said brush and be grasped therewith
to retain the jacket in place.
2. A tooth cleaner comprising, in combination,
a tooth brush including a handle having bristles,
20 adjacent one end, a jacket for said bristles, a

short tab on one end of said jacket, a long tab
on the opposed end, and means in said tabs to
coact with said handle and with each other to
retain the jacket in place.

3. A tooth cleaner comprising a jacket and 5
holding tabs consisting of a fabric strip of suffi-
cient length and width to form the jacket and
holding tabs, said strip being cut and folded in-
termediate its ends to provide a substantially rec-
tangular jacket adapted to be fitted over the 10
bristles of a tooth brush, a short tab extending
from one end of said jacket, a long tab extending
from the opposed end of said jacket, said tabs
each being apertured at their juncture with the
jacket to receive the ends of the tooth brush 15
handle therethrough, the short tab being aper-
tured adjacent its free end also to receive the
long tab therethrough whereby the jacket is se-
cured in place.

FRED VAN DER WERTH. 20
